Primary Examiner — Samantha Wood(74) *Attorney, Agent, or Firm* — Tyler A. Stevenson; Anna-lisa L. Gallo(57) **CLAIM**

We claim the ornamental design for a faucet, as shown and described.

DESCRIPTION

FIG. 1 is a front, top, left side perspective view of a faucet showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, bottom, left side perspective view thereof. Broken lines of the disclosure represent portions of the faucet that form no part of the claimed design.

1 Claim, 8 Drawing Sheets(56)
